UNITED STATES PATENT OFFICE.

PHILIS MAYOTTE, OF ESCANABA, MICHIGAN, ASSIGNOR OF ONE-HALF TO
SAMUEL B. RATHFON, OF SAME PLACE.

KNOCKDOWN BARREL.

SPECIFICATION forming part of Letters Patent No. 622,058, dated March 28, 1899.

Application filed July 23, 1898. Serial No. 686,672. (No model.)

To all whom it may concern:

Be it known that I, PHILIS MAYOTTE, of Escanaba, in the county of Delta and State of Michigan, have invented a new and Improved Knockdown Barrel, of which the following is a full, clear, and exact description.

My invention relates to improvements in barrels and similar packages, by which they may be knocked down or collapsed for convenience in shipping.

My invention consists of the novel features hereinafter shown and described.

Reference is to be had to the accompanying drawings, forming a part of this specification, in which similar characters of reference indicate corresponding parts in both the figures.

Figure 1 is an elevation of a barrel constructed according to my invention; and Fig. 2 is a cross-section thereof, taken on the line 2-2 in Fig. 1.

In certain lines of business, especially in shipping beer, it is a matter of considerable expense to return the empty barrels or kegs. This expense might be greatly reduced by 25 having a practical and simple knockdown barrel to be used for this purpose; and the object of my invention is to provide such a barrel.

The staves A of the barrel are formed like 30 the staves of ordinary barrels, and the barrel is also provided with top and bottom heads constructed like those of any ordinary barrel.

The hoops provided for the barrel consist 35 of chains B, which are secured to the barrel in such a manner as to prevent their movement lengthwise of the barrel and having

their ends so connected as to tighten the hoops and thus make the barrel tight. The links forming the chains which act as hoops vary 40 slightly in structure, the body of the chain being formed of links which are alike, while two end links are slightly different in construction from the body-links. The end links each have an aperture in their outer end

45 adapted to receive a tightening-bolt C, which passes through the end of one link and screws into the end of the other link. The links of the inner hoops or those nearest the center of the barrel are provided with flanges b, which 50 project inwardly and serve as a bearing-surface for the heads of the pins or bolts D, by

which the chains are secured to the barrel-staves. These pins or bolts D may pass entirely through the staves or only part way, as shown in Fig. 2. At their outer ends the 55 pins or bolts D extend into a slot between the flanges b, and they are provided with a head which engages the upper surface of the flanges b, thus permitting a slight circumferential movement of the chain while holding 60 the chain to the staves.

The links B', which form the body of the chain, are hinged to each other in the usual manner, while the end link B² receives the tightening-bolts C. All the links of the central hoops are preferably secured to the staves in the manner described. In the case of the end hoops or those nearest the heads only a few of the central links are secured to the staves. The remainder of the links are secured against longitudinal movement upon 70 the staves by means of pins E, which project from the staves and enter the space between the sides of the link. These links are not provided with the flanges b, as described for 75 the other links. These pins E permit the chain to be removed from the staves and will hold the chain in place when the barrel is set up. This construction is rendered necessary

by reason of the fact that when the barrel is 80 knocked down and the staves laid out flat the ends of the staves are separated. The adjustment of the links upon the staves which would be possible by the construction used for the central hoops would not be sufficient 85 to allow for the adjustment necessary for the end hoops.

For convenience in tightening the hoops the heads of the bolts are slotted, so that they may be engaged by a screw-driver. They 90 may also be made of square or hexagonal shape, so that they may be engaged by a wrench, if desired.

When it is desired to return the barrel constructed in accordance with my invention, the 95 hoops are loosened by withdrawing the bolts C, and the staves may then be laid out flat and the heads removed. By this means a number of barrels may be placed in the space which would otherwise be required for one 100 barrel and freight charges for the same would be correspondingly reduced.

The result of this barrel would be to cause the barrels to be returned in many cases where they are not now returned, and would thus result in a fewer number of barrels being needed.

Having thus fully described my invention, I claim as new and desire to secure by Letters Patent—

A knockdown barrel having hoops each 10 formed as a chain, the end links of the chain

being adapted to receive a tightening-bolt, certain links having longitudinal flanges on their inner edges, and pins secured to the staves and entering the slot between the flanges, the pins having heads extending over 15 the flanges, substantially as described.

PHILIS MAYOTTE.
